UNITED STATES PATENT OFFICE

2,427,195

ELECTRIC CIRCUIT BREAKER

Harold Ernest Cox, Dollis Hill, and Thomas Webster Wilcox, Harrow, England; assignors to General Electric Company, a corporation of New York.

Application June 1, 1945, Serial No. 597,022
In Great Britain October 20, 1944

15 Claims. (Cl. 200—148)

1 Our invention relates to electric circuit breakers and more particularly to electric circuit breakers of the fluid or gas blast type having separable contacts between which a blast of gas or fluid is directed for extinguishing arcs. Specifically our invention is an improvement on co-pending Boisseau et al. application, Serial No. 570,006, filed December 27, 1944, and assigned to the same assignee as the present application.

In circuit breakers of the kind referred to above it is frequent practice to provide circuit interrupting contacts which are normally held in engagement by spring pressure and so arranged that when the breaker is to perform an opening operation the admission of air or other fluid under pressure adjacent the contacts or into the chamber surrounding the contacts causes them to open by a predetermined amount allowing a fluid blast to flow through suitable arc extinguishing nozzles. In circuit breakers of this type the supply of fluid to the arcing chamber effects both separation of the contacts and the scavenging of the arcing space between the separating contacts. Where these circuit breakers employ a retracting rod-type contact a segmental finger-type sliding contact is generally required to carry the current to the movable contact element. This movable contact is often in butt engagement with an associated contact. The amount of current which can be carried by such butt-type contacts of a given material, depends chiefly upon the pressure exerted and in some measure on the area of the contact faces. Increase of the contact area beyond a certain amount does not necessarily provide increased conductivity because of the practicable impossibility of maintaining contact over the whole area and it may be said that there is a practical limit to current which can be carried efficiently by a single pair of contacts.

It is an object of our invention to provide a fluid blast circuit breaker with a contact arrangement in which there is practically no limit to the current which can be efficiently carried by the contacts.

It is another object of our invention to provide a new and improved electric circuit interrupter in which the contact structure comprises a plurality of pivotally mounted blades or sectors normally urged into engagement with a cooperating contact.

It is another object of our invention to provide a new and improved gas blast circuit breaker in which the contact structure is readily rendered accessible for inspection, replacement or repair.

2 Further objects and advantages of our invention will become apparent as the following description proceeds, and the features of novelty which characterize our invention will be pointed out with particularity in the claims annexed to and forming a part of this specification.

For a better understanding of our invention reference may be had to the accompanying drawing in which Fig. 1 is an elevational view partly in section of a high voltage electric circuit breaker embodying the present invention, and Fig. 2 is a sectional view taken on line 2—2 of Fig. 1 assuming that Fig. 1 shows a complete device with no parts cut away.

15 Although our invention may be applied to a circuit interrupter having a single set of arc extinguishing contacts, we have chosen to illustrate our invention as applied to a circuit interrupter comprising two sets of arcing contacts arranged in series so as to form two breaks in series generally referred to as a series multiple-break gas blast circuit breaker. It will be understood that a polyphase circuit interrupter would employ an arrangement such as is disclosed in Fig. 1 for each phase of the circuit.

Referring now to the drawing, the electric circuit interrupter comprises an interrupting unit generally indicated at 1 which is connected in series with an isolating switch 2 between circuit terminals 3 and 4 of an associated circuit to be controlled. The interrupting unit 1 comprises an arcing chamber including an upper chamber section 5 defined by a tubular member 6 of insulating material and a lower chamber section 7 defined by a similar tubular member 8 formed of insulating material. If desired, the tubular members 6 and 8 may be enclosed in a weather resistant insulating material, such as porcelain, or preferably may be formed of an insulating material which is weather resistant.

The tubular members 6 and 8 are arranged in axial alignment with the member 8 arranged below the member 6. Preferably the member 8 is arranged in sealing engagement with a suitable flange 9 supported on a conducting casting 10 which in turn may be supported on a suitable porcelain insulator or the like (not shown). Casting 10 includes a passageway 11 whereby fluid under pressure may be supplied to chamber sections 1 and 5. Casting 10 also is provided with a tubular member 12 which extends into chamber 7 in coaxial arrangement with lower insulating member 8. Tubular member 12 is provided with an annular contact surface 13 surrounding a central orifice 14 through which fluid under pres-

sure may flow into tubular member 12 and thence out to atmosphere through a passageway 15.

In sealing engagement with the upper end of tubular insulating member 8 defining arcing chamber 7 is a flanged member 16 provided with a hinge member 17. The lower end of tubular insulating member 6 is arranged in sealing engagement with a flanged member 18 similar to the flanged member 16 and provided with a cooperating hinge member 19 pivotally related to hinge member 17 by a pin 20. In normal operation of the circuit breaker the flanges 16 and 18 are united in sealed relationship by suitable fastening means, such as bolts 21, passing through the flanges thereof. However, access to the interior of each chamber section 5 and 7 through the ends of tubular members 6 and 8, which are adjoining, may be obtained by removing bolts 21 and pivoting the upper chamber 5 about pin 20 to the position shown in phantom in Fig. 1, or even further so that the adjoining ends of the chamber sections are in a horizontal plane.

In sealing engagement with the top of the upper tubular insulating member 6 is a flanged conducting member 22 electrically connected to line terminal 4. Flanged conducting member 22 supports a tubular conducting member 23 similar to tubular member 12 and arranged within chamber section 5 in coaxial relationship with tubular insulating member 6. Tubular member 23 terminates in an annular contact surface 24 surrounding an orifice 25 so that fluid or gas under pressure may pass through orifice 25, through tubular member 23 and thence to atmosphere. In order to prevent rain and snow from entering tubular member 23 we preferably provide a hood 26 supported from tubular member 23 by suitable means indicated at 27.

The tubular members 12 and 23 provided with annular contact surfaces 13 and 24, respectively, each comprise the stationary contact of the two sets of relatively separable contacts required in a gas blast breaker of the series multiple-break type. These annular contacts 13 and 24 are spaced apart along the axis of the arcing chamber so that one of these stationary contacts is disposed in each chamber section 5 and 7.

Interposed between stationary arcing contacts 13 and 24 is a unitary contact assembly generally indicated at 28 which might comprise a pair of retractable contacts one adapted to engage with each of the arcing contacts 13 and 24. As illustrated, the unitary contact assembly 28 comprises a unitary casting including a central cylindrical chamber member 29 symmetrically disposed about a pair of spaced plates 30 and 31. The plates 30 and 31 are of the same diameter as the flanges 16 and 18 between which they are disposed, and are provided with a plurality of passageways 32 therethrough so that fluid under pressure may readily flow from chamber section 7 to chamber section 5. It will be observed that the spaced plates 30 and 31 serve as a flange which constitutes the sole support for the entire movable contact structure contained within the interrupter so that by arranging this flange in clamping relationship between flanges 16 and 18 of the spaced chambers 7 and 5 as shown, the removal of the common clamping bolts 21 is all that is necessary for disconnecting the whole unitary movable contact assembly 28 from the rest of the apparatus, thereby enabling a replacement unitary assembly to be substituted in short order.

Cylindrical chamber member 29 is disposed between and in axial alignment with tubular mem-

bers 12 and 23 with the ends thereof spaced a predetermined distance from stationary annular contacts 13 and 24, respectively. The end of cylindrical chamber 29 adjacent annular contact 13 is provided with an orifice 33 while the end of cylindrical chamber 29 adjacent annular contact 24 is provided with an orifice 34. Cylindrical chamber 29 may function in the same manner as the arrangement disclosed and claimed in co-pending Wilcox application Serial No. 539,738, filed June 10, 1944, and assigned to the same assignee as the present application. Fluid under pressure entering cylindrical chamber 29 through orifices 33 and 34 may escape to atmosphere through a plurality of openings 35 leading to horizontal passageways 36 between plates 30 and 31 interposed between the vertical passageways 32.

Radially disposed around the orifice 34 are a plurality of contact fingers 37, preferably pivotally mounted as is indicated at 38, to integral extensions 39 of cylindrical chamber member 29. Radially disposed movable contacts 37 are biased into engagement with annular contact 24 by virtue of spring means 40 arranged in any suitable manner, such for example, as the compression arrangement illustrated in Fig. 1. Identical radially disposed contacts are provided around orifice 33 and these are characterized by the same reference numerals.

For minimizing the expenditure of air or other extinguishing fluid flowing between the fixed and movable contact structures from chambers 5 and 7, insert members 41, which are shown as insulating sectors in Figs. 1 and 2, may be provided for blocking the intervening spaces between adjacent radially disposed contacts 37. Preferably, as indicated in Fig. 1, these insert members 41 are of the same thickness as the contacts 37 so that when the latter are pivoted to their fully opened position, in which position they lie horizontally seated against the disk-like surface surrounding the orifices 33 and 34, the combined outer face of contacts 37 and insert members 41 constitutes a substantially unbroken plane disk-like surface which is in spaced relationship from the adjacent disk-like surface of arcing contacts 13 and 24. This arrangement provides for a smooth streamlined inward radial flow between the separated contacts for the extinguishing fluid issuing from chambers 5 and 7.

In view of the above description, it will be clear that the contact structure of our invention may be regarded, in one aspect, as comprising two cooperating spaced disks between which an extinguishing fluid is caused to flow, portions of which disks constitute resilient conducting members for electrically bridging the gap therebetween. Heretofore, in comparable nozzle contact type interrupters, it has been conventional to cause separable movement of the whole cylindrical contact element, whereas, in accordance with our invention, only such portions of the nozzle contact structure as are essential for conducting current bridging across the nozzles are made movable, thereby reducing the mass of movable contact parts to a minimum. Hence, the smaller contact members open faster, renewals thereof are more economical, in addition to which better current transfer conditions across the separable contacts are afforded by virtue of providing more numerous positive points of contact.

In order to operate the circuit breaker embodying our invention fluid under pressure, such as air or other gas, is supplied to passageway 11

in casting 10 and flows in the direction of the arrows indicated in Fig. 1 into chamber section 1 and also into chamber section 5 through vertical passageways 32. The fluid under pressure in chamber sections 5 and 1 presses movable contacts 37 away from the stationary annular contacts 13 and 24 to draw a plurality of arcs between contacts 37 and stationary annular contacts 13 and 24. This fluid under pressure passes at high velocity through orifices 14, 33, 25 and 34 thereby rapidly extinguishing the arcs which are drawn. The fluid passing through orifices 14 and 25 flows in the direction of the arrows to atmosphere, as is shown in Fig. 1. The fluid passing through orifices 33 and 34 exhausts to atmosphere through horizontal passageways 36 between plates 30 and 31, as is clearly indicated by the arrows in Fig. 1.

For contributing toward holding the contacts 37 in their fully opened position against the bias of their closing springs, advantage is taken of the difference in fluid pressure that exists between the upstream and downstream regions on either side of the orifices 33 and 34, and which differential is known to be in the ratio of about 2 to 1. Accordingly, we provide a suitable port or ports 42 through the end walls of the cylindrical chamber 29 in way of the inner end of each contact member 31, and which end walls provide convenient seating surfaces for establishing a limiting open position for contacts 37. One such port is clearly shown through both the upper and lower ends of chamber 29 to the left of and adjacent to the central orifices 34 and 33 respectively. Consequently, with the contacts 37 pivoted to their limiting open horizontal position, the higher pressure on their outer faces effectively preponderates over the lesser pressure at their inner faces due to the presence of ports 42 which latter communicate to the region of lower pressure within the cylindrical chamber 29 and which region exhausts to atmosphere via the openings 35 and passageways 36.

Before the flow of air through passageway 11 is stopped but after the arcs are extinguished in interrupting unit 1, disconnecting or isolating contact 2 is moved to the open position, whereupon the gas flow to the arcing chamber may be interrupted and radially disposed contacts 37 permitted to reclose.

When it is desired to close the circuit the isolating switch 2 alone may be operated, or if preferred fluid under pressure may be supplied to the arcing chamber during the closing of isolating switch 2 whereupon radially disposed contacts 37 will be opened and the circuit finally closed at these arcing contacts when the fluid blast is shut off.

It will be observed that the radially disposed contact fingers 37 when in their fully opened position provide short arc gaps between associated annular contacts 13 and 24, which arc gaps should be the so-called "preferred gap" for more satisfactory arc interruption, along the lines of the arrangement disclosed and claimed in co-pending Paul et al. application, Serial No. 586,892, filed April 6, 1945, and assigned to the same assignee as the present application.

Although in the preferred embodiment shown, both the fixed and separable contact structures are each provided with an orifice so that the extinguishing blast of fluid may exhaust in opposite axial directions, it will be apparent that the resilient contact arrangement of our invention

will function in the same advantageous manner if but a single exhaust passage were provided.

It will be observed that with the hinged construction of Fig. 1 the unitary contact assembly 5 containing all of the movable parts of the interrupting unit 1 may be readily removed for inspection, repair or replacement.

While we have shown and described a particular embodiment of our invention, it will be obvious to those skilled in the art that various changes and modifications may be made without departing from our invention in its broader aspects and we, therefore, aim in the appended claims to cover all such changes and modifications as fall within the true spirit and scope of our invention.

What we claim as new and desire to secure by Letters Patent of the United States is:

1. In a fluid blast electric circuit breaker comprising an arcing chamber, a plurality of relatively separable contacts in said chamber, a source of fluid under pressure, means for supplying fluid under pressure from said source to said arcing chamber, an orifice in one of said relatively movable contacts through which fluid under pressure supplied to said chamber exhausts thereby providing a fluid blast, the other of said contacts comprising plural conducting members disposed radially around said orifice, and means for urging said radially disposed members independently into engagement with said one contact, said radially disposed members being arranged to impede the flow of said fluid towards said orifice so that they are moved to disengaging position when said fluid is supplied to said chamber.

2. In a fluid blast electric circuit breaker comprising an arcing chamber, a plurality of relatively separable contacts in said chamber, a source of fluid under pressure, means for supplying fluid under pressure from said source to said arcing chamber, an orifice in one of said relatively movable contacts through which fluid under pressure supplied to said chamber exhausts thereby providing a fluid blast, the other of said contacts comprising plural conducting members spaced radially around said orifice, and spring means for urging said radially spaced members independently into engagement with said one contact, said members being arranged to impede the flow of said fluid towards said orifice so that they are moved to disengaging position when said fluid is supplied to said chamber, and means for blocking the intervening spaces disposed between said plural conducting members.

3. A fluid blast electric circuit breaker of the series multiple break type comprising a pressure chamber containing groups of radially spaced separable contacts to which a supply of pressure fluid is directed for effecting both the separation of the contacts and the scavenging of the arcing space between the separated contacts, wherein the pressure chamber is composed of at least two chamber sections hinged together at adjoining ends so that the one section containing at least one of the contacts can be swung into a position whereby then to afford access to the interior of each section through the ends which were adjoining.

4. In a fluid blast electric circuit breaker comprising a pressure chamber, a pair of relatively separable contacts in said pressure chamber, and a source of fluid under pressure for supplying a blast of fluid adjacent said contacts for arc extinguishing purposes, said pressure chamber being composed of at least two chamber sections

hinged together at adjoining ends so that the one section containing at least one of the contacts can be swung into a position whereby then to afford access to the interior of each section through the ends which were adjoined.

5. In a fluid blast electric circuit breaker of the series multiple-break type, an arcing chamber, a plurality of pairs of serially arranged relatively movable contacts in said chamber, means for supplying fluid under pressure to said chamber for effecting arc extinction upon separation of each of said pairs of relatively movable contacts disposed within said chamber, said pairs of contacts being disposed at different positions axially of said chamber so that said chamber comprises a plurality of chamber sections in each of which is accommodated one of said pairs of relatively movable contacts, means for hingedly connecting said chamber sections together in end-to-end relation so that one section together with a contact contained therein can be swung into a position rendering accessible those parts within the sections which are nearest the adjoining ends thereof.

6. In a fluid blast electric circuit breaker, an arcing chamber, a pair of relatively movable contacts in said chamber, means for supplying fluid under pressure to said chamber for effecting arc extinction upon separation of said contacts disposed within said chamber, each of said contacts being disposed at a different position axially of said chamber so that said chamber comprises two chamber sections in each of which is accommodated one of said relatively movable contacts, and means for hingedly connecting said chamber sections together in end-to-end relation so that one section together with the contact contained therein can be swung into a position rendering accessible those parts within the sections which are nearest the adjoining ends thereof.

7. In a fluid blast electric circuit breaker, an arcing chamber, a pair of serially arranged relatively movable contacts in said chamber, means for supplying fluid under pressure to said chamber for effecting arc extinction upon separation of said relatively movable contacts disposed within said chamber, said chamber comprising a plurality of chamber sections with the contacts arranged to engage each other at the junction between said chamber sections, and means for hingedly connecting said chamber sections together in end-to-end relation so that one section together with a contact contained therein can be swung into a position rendering accessible those parts within the sections which are nearest the adjoining ends thereof, one of said contacts being arranged in a unitary assembly so as to be readily withdrawn from one of said chamber sections for repair or replacement.

8. In a gas blast electric circuit breaker of the series multiple-break type comprising an arcing chamber, a plurality of relatively separable contacts in said chamber, said contacts being disposed at different positions axially of said chamber so that said chamber comprises a plurality of spaced chamber sections in each of which is accommodated a set of relatively separable contacts, a source of gas under pressure, means for supplying gas under pressure from said source to each of said arcing chamber sections, an orifice in one of each of said sets of relatively movable contacts through which gas under pressure supplied to each associated said chamber section may escape thereby providing a gas blast through each of said orifices, the others of said contacts

of each set being disposed radially around said orifice, means for urging said radially disposed contacts into engagement with its associated contact containing said orifice, said radially disposed

- 5 contacts being arranged to impede the flow of
said fluid toward said orifices so that said contacts are moved to disengaging position for in-
terrupting the circuit therethrough when said fluid is supplied to said chamber sections, a uni-
10 tary contact assembly structure of which each said set of radially disposed contacts forms a part including a transverse supporting flange therefor, said flange constituting the spacing means separating said chamber sections, and
15 means for securing said spaced chamber sections disconnectably to said flange whereby said unitary contact assembly is rendered readily replaceable.

9. In a fluid blast electric circuit breaker com-
20 prising an arcing chamber, a plurality of relatively separable contacts in said chamber, a source of fluid under pressure, means for supplying fluid under pressure from said source to said arcing chamber, an orifice in one of said relatively movable contacts through which fluid under pressure supplied to said chamber exhausts thereby providing a fluid blast, one of said contacts comprising plural conducting members disposed radially around said orifice, said radially
25 disposed members being arranged yieldingly to impede the flow of gas toward said orifice so that they are moved to open circuit position when said fluid is supplied to said chamber.

10. In a fluid blast electric circuit breaker com-
30 prising an arcing chamber, a source of fluid under pressure, means for supplying fluid under pressure from said source to said arcing chamber, means defining an orifice in said chamber through which fluid under pressure supplied to said chamber may escape thereby providing a fluid blast, separable contact structure for producing an arc to be extinguished comprising a plurality of yieldable conducting members disposed radially about said orifice, means for biasing each said
35 member individually to closed circuit position, and means for causing movement of each said member to open circuit position, said last mentioned means being responsive to pressure fluid supplied to said chamber.

11. A fluid blast electric circuit interrupter comprising a first arcing chamber, a second arcing chamber arranged in spaced axial relationship with respect to said first chamber, a fixed arcing contact mounted axially in each chamber
40 at the end thereof adjacent the other chamber, a unitary contact assembly structure including two conductively connected independently movable contacts respectively associated with said fixed contacts for drawing a series interrupting
45 arc in each said chamber, means for biasing each said movable contact into engagement with its associated fixed contact, means for supplying gas under pressure to said first and second chambers, means responsive to fluid in each chamber for moving the associated movable contact out of engagement with the fixed contact therein, certain of said contacts being hollow for directing an axial blast therethrough, said unitary contact assembly including a transverse supporting
50 flange constituting the spacing means for separating said first and second chambers one from another, and means for securing said first and second chambers disconnectably to said flange whereby said unitary contact assembly is rendered readily removable and replaceable.

70

75

12. A fluid blast electric circuit interrupter comprising a first arcing chamber, a second arcing chamber arranged in spaced axial relationship with respect to said first chamber, a fixed arcing contact mounted axially in each chamber at the end thereof adjacent the other chamber, a unitary contact assembly structure including two conductively connected independently movable contacts respectively associated with said fixed contacts for drawing a series interrupting arc in each said chamber, means for biasing each said movable contact into engagement with its associated fixed contact, means for supplying gas under pressure to said first and second chamber, means responsive to fluid in each chamber for moving the associated movable contact out of engagement with the fixed contact therein, certain of said contacts being hollow for directing an axial blast therethrough, said unitary contact assembly including a transverse supporting flange constituting the spacing means for separating said first and second chambers one from another, and means for clamping said flange between said first and second chamber whereby said unitary contact assembly is rendered readily removable and replaceable.

13. In a fluid blast circuit interrupter, arcing contacts comprising two cooperating structures forming two substantially disk-like spaced surfaces having a preferred gap therebetween during circuit interruption, at least one of said structures including plural resilient conducting portions biased to bridge said gap electrically, and means for directing a blast of pressure fluid through said gap between said cooperating structures, said resilient portions being positioned in said gap so as to impede the flow of said fluid blast therethrough whereby they are moved by said fluid blast from their biased position to circuit interrupting position, the impeding surfaces of said resilient conducting portions being constructed to form contributory parts of one of said disk-like surfaces when said resilient conducting portions are in the circuit interrupting position.

14. In a fluid blast circuit interrupter, arcing contacts comprising two cooperating structures forming two substantially disk-like spaced surfaces having a preferred gap therebetween dur-

ing circuit interruption, an orifice in one of said structures forming a blast passage piercing one of said surfaces, at least one of said structures including plural resilient conducting portions arranged radially about said orifice and biased to bridge said gap electrically, and means for directing a blast of pressure fluid between said cooperating structures and through said orifice, said resilient portions being positioned in said gap so as to impede the flow of said fluid blast therethrough whereby they are moved by said fluid blast from their biased position to circuit interrupting position, the impeding surfaces of said resilient conducting portions being constructed to form contributory parts of one of said disk-like surfaces when said resilient conducting portions are in the circuit interrupting position.

15. In a fluid blast circuit breaker, an arcing chamber, relatively movable contacts disposed in said chamber for drawing an arc to be extinguished, one of said contacts being of the pivotal gate type biased to conducting engagement with another of said contacts, means for directing a blast of said pressure fluid between said contacts, said gate contact being positioned so as to impede the flow of said fluid blast whereby it is moved toward circuit open position by said fluid blast, means including a seating surface for establishing a limiting open position for said gate contact, and a port through said seating surface in way of said gate contact and communicating to a region external to said chamber for producing a pressure differential which is effective to draw said contact toward and maintain it against said seating surface.
